UNITED STATES PATENT OFFICE.

JAMES H. WILSON AND STEVENS A. BENNETT, OF CHICAGO, ILLINOIS, ASSIGNEES TO
WILSON & BENNETT MFG. CO., A CORPORATION OF ILLINOIS.

TOP FOR OIL-TANKS.

1,178,895.

Specification of Letters Patent. Patented Apr. 11, 1916.

Application filed June 5, 1911. Serial No. 631,224.

To all whom it may concern:

Be it known that we, JAMES H. WILSON and STEVENS A. BENNETT, citizens of the United States, residing at Chicago, in the county of Cook and State of Illinois, have invented certain new and useful Improvements in Tops for Oil-Tanks, of which the following is a specification.

This invention relates more particularly to improvements in oil-tanks, such as are usually provided with a pan or depression in the top for convenience in filling cans or other small receptacles. A removable pump is commonly inserted through the bottom 15 of this pan, the bottom also being provided with a drain to allow the overflow or drip to run back into the tank. These cans are frequently made of galvanized iron, and heretofore it has been common to solder the 20 bottom of the pan into position, but such soldering is apt to become loose on account of the galvanizing material giving way, and such method of attachment has not proven satisfactory.

It is the object of the present invention to provide an improved form of top for tanks, which may be cheaply and quickly made and placed in position, which will strengthen the tank, which will provide a 30 sufficiently tight closure, and which will have such other advantages as will appear from the following description.

We have illustrated a preferred form of our invention in the accompanying drawings, in which—

Figure 1 is a plan view of a tank provided with our improved top; Fig. 2 is a sectional view of the same; and Fig. 3 is a detail showing a blank used for forming 40 the pan portion of the top.

As shown in these drawings, 4 represents a tank of any ordinary or preferred form of construction, such tanks being usually provided, around the top, with a bead 5. In 45 the present instance, we have shown the pan portion 6 of our improved top as extending over about one-half of the tank, although it may be made larger or smaller if desired, but this is the preferable arrangement. This pan portion 6 is formed from a blank 7 of suitable material, such as sheet iron or the like. It comprises a bottom 8 having an upwardly extending flange 9 adapted to fit against the inner surface of 55 the side of the tank 4, the upper edge of

this flange being bent or formed as indicated at 10 to fit closely around the bead 5. A corresponding straight flange 11 extends upwardly from the diametrical or straight side of the bottom 8 and connects with an integrally formed horizontal strip 12 which extends diametrically across the top of the tank and has its ends 13 bent or curled around the bead 5. The opposite edge 14 of the strip 12 is bent downwardly and back toward the strip, thereby stiffening the strip and also serving to furnish hinge-like connection for the other half 15 of the top. This hemispherical or half top 15 is provided, along its diametrical edge 16, with an upwardly bent flange which engages with the flange or edge 14 and its circumferential edge is provided with a flange 17 which is adapted to snap down over the bead 5 to hold this portion of the top in position, although being left sufficiently free so that this portion of the top may be removed when desired. The bottom 8 of the pan 6 is preferably provided with a hole 18, through which a pump may be inserted, and with a hole 19 to allow the overflow or drip to return into the tank. A swinging cover 20 for covering the pump and pan may be hinged to the cross strip 12 in the usual manner, if desired. Our combined pan and cover member is made from a blank 7, substantially of the form shown in Fig. 3, such blank being bent or curved at points, as indicated by the dotted lines, in order to form the various parts above described. After the blank has been cut out, it is pressed by means of suitable dies to form the pan portion and is then inserted in position in the top of the tank, and then the flanges 10 and 13 are turned over to engage with the bead 5. By means of this construction, it will be seen that the pan may be cheaply and quickly formed and inserted in position, and such pan will not only be rigid and substantial but will strengthen the top of the tank. After the pan portion is fastened in position, the flange 16 of the semicircular member 15 is hooked under the flange 14, and the outer depending flange 17 is then pressed downwardly over the bead 5, thereby securing this half of the top in place.

Having thus described our invention, which, however, we do not wish to limit to the exact form of construction herein shown and described, except as set forth in

the appended claims, what we claim and desire to secure by Letters Patent is:

1. The combination with a tank having a bead around the upper edge thereof, of a pan having an upwardly extending peripheral flange fitting within the upper end of said tank, the edge of said flange being bent to engage with the bead around the top of the tank, said pan being also provided 10 with an upwardly extending, integrally formed flange extending across the tank, said flange connecting with a horizontal crosspiece, the ends of which crosspiece are bent to engage with the bead at the top 15 of the tank.

2. The combination with a cylindrical tank having a bead around the upper edge thereof, of a substantially semicircular top member provided with an upwardly extending peripheral flange, the edge of said flange 20

being bent to engage with said bead, said top member also being provided with a substantially diametrical, upwardly extending, integrally formed flange connecting with an integrally formed horizontal cross-piece, 25 the ends of said crosspiece also being bent to engage with the bead, said crosspiece having a downwardly turned edge, and a substantially semicircular top member having one edge bent to engage with the down- 30 wardly turned edge of said crosspiece and having its outer periphery provided with a downwardly turned flange adapted to fit over said bead.

JAMES H. WILSON.
STEVENS A. BENNETT.
